UNITED STATES PATENT OFFICE

EDWARD L. TORRISON, OF SAN FRANCISCO, CALIFORNIA, ASSIGNOR TO E. WAYNE PHILLIPS, OF OAKLAND, CALIFORNIA

SANDPAPERING AND RUBBING MACHINE

Application filed July 23, 1928. Serial No. 294,687.

The invention forming the subject matter of this application relates to sand papering and rubbing machines, and particularly to the type of sand papering or rubbing machines which are operated by compressed air or other fluid under pressure.

The primary object of the invention is the provision of a sand papering or rubbing machine in which a sand papering or rubbing barrel is reciprocated, and in which means are provided for controlling the flow of fluid under pressure to act on opposite ends of the barrel, the means being so constructed as to prevent violent vibration of the device during the reciprocation of the sand paper or other finishing plate moved by said barrel.

Another object of the invention is the provision of a sand papering or rubbing machine in which a valve is operated for admitting fluid under pressure so as to act alternately on the opposite heads of a barrel, slideable on a stationary piston, and which valve is slideable in the piston and is so partitioned and so actuated by the opposite heads of the barrel as to direct the fluid under pressure toward the head of the barrel which is closest to a piston end.

A still further object of the invention is the provision of a cylindrical, sliding valve in a stationary piston, upon which piston is slideable a barrel carrying a sand papering or rubbing device, the cylindrical valve being alternately actuated by the opposite heads of the barrel at the ends of their respective strokes so as to enable said valve to direct the flow of the fluid under pressure against the head of the barrel closest to an end of the piston; the heads being adapted to receive the adjacent end of the cylindrical valve in such a manner as to provide an air cushion, thereby preventing the violent vibration of the valve or of the barrel.

With the above mentioned objects and other objects in view, the invention consists in the novel construction and combination of parts hereinafter described, illustrated in the accompanying drawing, and set forth in the claims hereto appended, it being understood that various changes in the form, proportion, size, and minor details of construc-

tion within the scope of the claims may be resorted to without departing from the spirit or without sacrificing any of the advantages of the invention.

In the drawings:

Figure 1 is a side elevation of the sand papering and rubbing machine;

Figure 2 is an end view of the same;

Figure 3 is a longitudinal section of the machine;

Figure 4 is a sectional view of the sand papering or rubbing machine, the section being taken on the line 4-4 of Figure 3;

Figure 5 is a longitudinal section of the sand papering or rubbing machine, showing the barrel thereof at the end of its stroke opposite to the position shown in Figure 3, and also showing the position of the valve after the same is actuated by said barrel;

Figure 6 is a fragmentary sectional view of the machine showing the barrel in a position when the fluid under pressure is permitted to exert its force to the full surface of the barrel head; and

Figure 7 is a sectional view taken on the line 7-7 of Figure 6, showing the valve travel limiting means for the cylindrical valve.

Referring to the accompanying drawings, wherein similar reference characters designate similar parts throughout, the various figures described above adequately illustrate my invention, and the following detailed description is commensurate with the above mentioned drawings in enabling an artisan to construct and assemble the constituent parts of the same.

In carrying out my invention, I make use of a piston designated by the numeral 6. A concentric bore 7 extends throughout the piston 6, and in said bore is slidably disposed a cylindrical sliding valve 8. The piston is held stationary by the grasping of a handle, denoted in its entirety by the numeral 9, the handle being secured to the central portion of the piston by means of a bolt 11, the threaded end of which is fixedly secured into a corresponding threaded hole 12 in the piston 6. The head of the bolt 11 is countersunk into the handle 9 as shown in Figure 3, so as to

render the surface of the handle smooth. Thru the handle and thru the bolt 11 is an intake passage 13 in continuation of which is the intake opening 14 extending thru the piston 6 to the bore 7. An atmospheric outlet opening 16 is provided in the piston 6 at each side of the intake opening 14. The atmospheric openings 16 are equally spaced from the intake opening 14 and connect the bore 7 to the outside periphery of the piston 6.

15 A cylindrical barrel 17 is slideable upon the piston 6. The cylindrical barrel 17 is longer than the piston 6 so as to allow the reciprocation of the former upon the latter. In order to prevent the relative movement of the handle 9 around the barrel 17, arms 18 extend from the opposite sides of each end of the handle 9. The arms 18 are converging toward the barrel 17 and the ends thereof are arcuate so as to conform to the outside periphery of the barrel 17, at the same time bearing thereagainst when there is a tendency to turn the handle around the barrel.

25 It is to be understood that although a particular type of handle is shown, other styles of handles may be used for the same purpose. For instance, a single open U-shaped handle may be secured to the central portion of the piston and above the intake opening thereof, upon which the usual trigger control valve arrangement may be employed. In the present device, the flow of the fluid under pressure is controlled by a valve on the conduit leading to the intake passage 13.

The barrel 17 is terminated at one end thereof by a head 19 and at the other end thereof by a similar barrel head 21. The passage of the cylindrical sliding valve 8 is divided into two compartments by means of a partition 22 disposed substantially at the center of the valve 8. At one side of the partition 22 is a valve inlet opening 23 and on the other side of the partition is another valve inlet opening 24. Equally spaced from the respective valve inlet openings are valve outlet openings 26, one between each valve intake opening and the respective ends of the valve 8. It is to be noted that the ends of the cylindrical valve 8 protrude beyond the ends of the piston 6.

The movement of the valve 8 in the piston bore 7 is limited by means of pins 27 threadedly secured into corresponding holes at the opposite sides of the intake opening 14. The pins 27 cooperate with corresponding slots 28 in the periphery of the cylindrical sliding valve 8. The slots 28 are so dimensioned as to limit the movement of the sliding cylindrical valve 8 in such a manner as to stop said movement when either the valve inlet opening 23 or the valve inlet opening 24 is in alignment with the intake opening 14. In Figure 3, the valve 8 is

shown in such a position that the valve travel in the direction of the barrel head 21 reached its end and any further travel thereof is prevented by the pins 27. In this position, the valve inlet opening 23 is in alignment with the intake opening 14. 70

It is to be noted that the outlet openings 26 of the valve 8 are so spaced from the valve inlet openings that when the valve inlet opening 23 is in alignment with the intake opening 14, then the valve outlet opening 26 on the other side of the partition 22 is in alignment with the atmospheric outlet opening 16; and vice versa, when the valve inlet opening 24 is in alignment with the intake opening 14, then the other valve outlet opening 26 is in alignment with the respective atmospheric outlet opening 16 on the side of the partition 22 opposite to the inlet opening 24. The heads 19 and 21 are provided with concentric annular grooves corresponding to the cylindrical valve 8 so as to receive the ends of the valve 8 therein.

On the barrel 17 are provided downwardly extending bosses 29, one at each end of the barrel, upon which bosses is secured a plate 31 by means of screws 32. The plate 31 may be of any suitable material used for certain types of finishing. The plate may carry a sand paper block or a sheet of sand paper for sand papering the surface or may carry a rubbing or polishing member or other suitable finishing materials.

The device operates as follows: The air is admitted thru the intake passage 13 and intake opening 14 and when the valve and the barrel are in the position shown in Figure 3, then the air enters into the valve 8 thru the valve inlet opening 23. The air pressure is then exerted both upon the partition 22 and upon the portion of the head 19 within the annular groove 20. The action of the fluid under pressure cannot move the valve 8 because its movement in the direction of the head 21 is limited by the engagement of the ends of the slots 28 with the pins 27. Thus, the pressure exerted on the head 19 moves the head 19 away from the respective end of the piston 6, thereby moving the barrel 17. 100 105 110

In order to allow the free movement of the barrel 17 unobstructed by the securing bolt 11, a slot 33 is provided in the barrel 17, which slot is slidable around the bolt 11. The slot 33 is of sufficient length to allow the full stroke of the barrel 17 as hereinafter described. During the movement of the barrel 17 when the barrel head 19 moves away from the end of the piston 6, the barrel head 21 moves toward the other end of the piston 6, and the annular groove 20 in the head 19 slides off the end of the valve 8, thereby allowing fluid under pressure to enter the chamber formed between the head 19 and the adjacent end of the piston 6. In Figure 6, I show the barrel 17, the valve 8, and the piston 6 in the 120 125 130

relative position just after the annular groove 20 slid off the end of the valve 8. Now, the full power of the compressed air is applied upon the inside surface of the head 19, and the barrel 17 is moved toward the end of its first stroke. At the end of this stroke, the groove 20 of the head 21 slides upon the adjacent head of the valve 8. The air in the annular groove 20 is compressed by the end of the valve 8 and forms an air cushion or shock absorber thereat for preventing a knock of the barrel head upon the valve 8. The force thus exerted by the head 21 moves the valve 8 in the direction of the head 19. The movement in this direction is limited by the abutting of the other end of the slots 28 against the pins 27. By this time, the valve inlet opening 24 is brought in alignment with the intake opening 14, and the valve outlet opening 26 on the opposite side of the partition 22 is in alignment with the corresponding atmospheric opening 16.

Now, the compressed air passes thru the valve inlet opening 24 into the valve 8 so as to be directed thereby against the head 21, reversing the movement thereof in a direction away from the adjacent end of the piston 6. This movement now brings the other head 19 toward the corresponding end of the piston 6 until the end of its stroke, at which time the annular groove 20 in the head 19 engages the end of the valve 8 and moves the same in the direction of the head 21, thereby bringing again the valve inlet opening 23 in alignment with the inlet opening 14 and also bringing the other outlet opening in alignment with the corresponding atmospheric outlet opening 16.

It is to be noted that the air cushion in the annular grooves 20 also results in the spacing of the inside face of the heads 19 and 21 from the respective ends of the piston 6, at the end of their respective strokes. Thus, it is evident that all knocking impacts at the ends of the strokes are effectively obviated.

It will be recognized that a particularly simple device is provided in which the use of a plurality of pistons is eliminated and in which the barrel is slidable on a piston and the full force of the compressed fluid or air is applied to the respective head of the barrel to result in its motion to the end of its stroke. It will also be recognized that at the end of each stroke, the valve is positively operated so as to direct the air toward the opposite head, thereby reversing the movement of the barrel 17. The air cushions between the ends of the valve 8 and the inside ends of the annular groove 20 and the air cushions formed between the inside surface of the heads 19 or 21 and the adjacent end face of the piston 6 effectively prevent the violent vibration and knocking of the tool.

The latter air cushion is formed on account of the closing of the valve end in the groove

20, before all the air is exhausted from between the heads 19 or 21, and the adjacent end of the piston 6, thus forming a chamber at the said end of the piston from which the air is not exhausted.

It is merely necessary to hold the tool by the handle 9, place the finishing surface of the plate 31 upon the object to be sand papered, polished, rubbed, or otherwise finished, and then by admitting compressed air thru the passages 13, the barrel 17 is continuously reciprocated upon the piston 6, effectively reciprocating the rubbing surface, thereby finishing the object desired. The device is a unitary character and does not require any careful setting up, and therefore it is readily adaptable to be operated by the labor ordinarily available.

I claim:

1. In a device of the character described, a supporting member having an inlet opening and exhaust opening therein; a reciprocatory member slidable on the supporting member, the ends of said reciprocatory member enclosing chambers at the respective ends of the supporting member; a valve slidable in the supporting member in operative relation to said inlet and outlet openings, said valve being adapted to be actuated by the said reciprocatory member so as to alternately direct a fluid under pressure from the said inlet opening into one of said chambers and to connect the other chamber with one of the exhaust openings, thereby causing the reciprocation of said reciprocatory member; and a surface finishing element carried by said reciprocatory member.

2. In a device of the character described, a supporting member having a longitudinal passage therethru, and having an inlet opening and outlet opening connecting to said passage; a reciprocatory member slidable on the supporting member, the former being longer than the latter; a valve slidable in the said passage, said valve being so actuated alternately by the opposite ends of the reciprocatory members as to direct a fluid under pressure against the end of the reciprocatory member which is closest to an end of the supporting member, and to allow the exhaust of fluid from the other end of the reciprocatory member; and a surface finishing element carried by said reciprocatory member.

3. In a device of the character described, a piston; means for supporting the piston, said piston having an inlet and outlet opening therein; a barrel slidable on the piston, the barrel being longer than the piston, the ends of the barrel enclosing a chamber at each end of the piston; a valve slidable in the piston and being adapted to be so actuated by the ends of the barrel as to alternately direct a fluid under pressure from said inlet opening to one of the chambers, and allow the

exhaust of the fluid from the other chamber; and a surface finishing element carried by the barrel.

4. In a device of the character described, a piston adapted to be held in stationary position, said piston having a longitudinal passage therethru and having an inlet and exhaust opening therein, communicating with the said passage; a barrel being longer than the piston so as to enclose a chamber at each end of the piston, said barrel being slidable on the piston; a tubular valve slidable in the passage; a partition in the valve for dividing the same, said valve having an inlet and an outlet opening at each side of the partition, so disposed that an inlet opening on one side of the partition and an outlet opening on the opposite side of the partition are simultaneously brought in operative relation to the respective openings of the piston; the ends of the barrel being adapted to alternately actuate said valve so as to cause the same to direct a fluid under pressure from the piston inlet opening against the barrel end closest to an end of the piston, and to exhaust the fluid from the chamber at the other end of the piston; and a surface finishing element carried by the barrel.

5. In a device of the character described, a piston adapted to be held in stationary position, said piston having a longitudinal passage therethru and having an inlet and exhaust opening therein, communicating with the said passage; a barrel being longer than the piston so as to enclose a chamber at each end of the piston, said barrel being slidable on the piston; a tubular valve slidable in the passage; a partition in the valve for dividing the same, said valve having an inlet and an outlet opening at each side of the partition, so disposed that an inlet opening on one side of the partition and an outlet opening on the opposite side of the partition are simultaneously brought in operative relation to the respective openings of the piston; the ends of the barrel being adapted to alternately actuate said valve so as to cause the same to direct a fluid under pressure from the piston inlet opening against the barrel end closest to an end of the piston, and to exhaust the fluid from the chamber at the other end of the piston; the ends of the tubular valve extending beyond the ends of the piston; the said barrel ends alternately abutting against the respective valve ends at the end of each stroke of the barrel; means for limiting the valve travel so as to cause the stopping of the valve in coacting position with the piston inlet and exhaust openings, and a surface finishing element carried by the barrel.

6. In a device of the character described, a piston adapted to be held in stationary position, said piston having a longitudinal passage therethru and having an inlet and exhaust opening therein, communicating with the said passage; a barrel being longer than the piston so as to enclose a chamber at each end of the piston, said barrel being slidable on

the piston; a tubular valve slidable in the passage; a partition in the valve for dividing the same, said valve having an inlet and an outlet opening at each side of the partition, so disposed that an inlet opening on one side of the partition and an outlet opening on the opposite side of the partition are simultaneously brought in operative relation to the respective openings of the piston; the ends of the barrel being adapted to alternately actuate said valve so as to cause the same to direct a fluid under pressure from the piston inlet opening against the barrel end closest to an end of the piston, and to exhaust the fluid from the chamber at the other end of the piston; the ends of the tubular valve extending beyond the ends of the piston; the said barrel ends alternately abutting against the respective valve ends at the end of each stroke of the barrel; means for limiting the valve travel so as to cause the stopping of the valve in coacting position with the piston inlet and exhaust openings, and a surface finishing element carried by the barrel.

7. In a device of the character described, a piston adapted to be held in stationary position, said piston having a longitudinal passage therethru and having an inlet and exhaust opening therein, communicating with the said passage; a barrel being longer than the piston so as to enclose a chamber at each end of the piston, said barrel being slidable on the piston; a tubular valve slidable in the passage; a partition in the valve for dividing the same, said valve having an inlet and an outlet opening at each side of the partition, so disposed that an inlet opening on one side of the partition and an outlet opening on the opposite side of the partition are simultaneously brought in operative relation to the respective openings of the piston; the ends of the barrel being adapted to alternately actuate said valve so as to cause the same to direct a fluid under pressure from the piston inlet opening against the barrel end closest to an end of the piston, and to exhaust the fluid from the chamber at the other end of the piston; the ends of the tubular valve extending beyond the ends of the piston; the said barrel ends alternately abutting against the respective valve ends at the end of each stroke of the barrel; means for limiting the valve travel so as to cause the stopping of the valve in coacting position with the piston inlet and exhaust openings, each barrel end having an annular groove therein for receiving the corresponding end of the tubular valve, so as to form an air cushion at said end, and a surface finishing element carried by the barrel.

8. In a device of the character described, a supporting member, a reciprocating casing surrounding and slidable on said supporting member, a valve for alternately directing a fluid under pressure against the ends of the casing, so as to cause the reciprocation there-

of, said valve being actuated by said reciprocating casing and a surface finishing element secured to the casing.

9. In a device of the character described, a supporting member having inlet and outlet openings therein for conducting a fluid under pressure, a reciprocating casing surrounding and slideable on said supporting member, a valve disposed in operative relation to said inlet and outlet openings, said valve being actuated by the said reciprocating casing, for alternately directing the fluid under pressure against the ends of the reciprocating casing and for allowing the exhaust of fluid from the end of the reciprocating casing not under fluid pressure and a surface finishing element secured to the casing.

10. A rubbing device comprising a piston, a reciprocating casing surrounding the piston, a valve for alternately directing a fluid under pressure against the ends of the casing, said valve being actuated by said casing, shock absorbers at the ends of the casing and a finishing element affixed to the casing.

11. A rubbing machine comprising a stationary piston, a casing surrounding the piston, a valve within the piston for alternately directing a fluid under pressure to the ends of the casing and a finishing element affixed to the casing.

In testimony whereof I affix my signature.
EDWARD L. TORRISON.
